UNITED STATES PATENT OFFICE.

ALBERT RUSH AND RALPH H. GREGOR, OF COLUMBUS, OHIO, ASSIGNEES TO THE KINNEAR MANUFACTURING COMPANY, OF COLUMBUS, OHIO, A CORPORATION OF OHIO.

DOOR AND OPERATING MECHANISM THEREFOR.

Application filed December 1, 1922. Serial No. 604,281.

This invention relates more particularly to a vertically folding door and has for its principal object to provide means whereby the closing of the door at the bottom is 5 tight. Other objects and advantages will appear from the following disclosure.

The invention is embodied in the example herein shown and described, the features of novelty being finally claimed.

10 In the accompanying drawings—

Figure 1 is mainly a front elevation of a folding door equipped with my invention, details of the counterbalancing means being shown in section.

15 Fig. 2 is a vertical section on the line II—II Fig. 1.

Figs. 3 and 4 are vertical sections showing how the opening of the door is initiated and the relative positions of the parts.

20 In the views 5, 5^a designate respectively upper and lower door sections which sections are hinged together at 6. The upper door section is slidingly hinged upon pins 7 on end brackets 8, 8^a, by means of hinging members 9, said hinging members being formed with slots 9^a so as to allow vertical play of the upper section in the initial opening and the final closing movements of the door as hereinafter set forth.

30 The means for raising the door sections includes spiral cone pulleys 10 and 10^a secured to the ends of shaft parts where they protrude beyond the end brackets and cords 11 connected to the lower corners of the

35 lower door section, the connection of the cords with the cone pulleys being at the larger ends thereof so that the pull of the cords increases as the door sections are raised and diminishes as the sections are lowered.

40 Where the door is of large dimensions and heavy the pull of the cords is augmented by a coil spring 12 attached at one end of the intermediate hollow shaft part 13 and at the other to the hub 14 of a wheel 15, said wheel

45 being adapted to be locked in adjusted position by a pin 16 inserted through a projection 17 on the end bracket 8 and any one of several holes in the rim of the wheel 15. By turning the wheel 15 in the proper direction 50 the spring can be tightened to place under tension the shaft 13 with its two opposite end parts pinned thereto and carrying the

cone pulleys so that the pull of the pulleys shall in a suitable measure counterbalance the weight of the sections and augment the 55 manual effort required to raise them.

In practice the right hand shaft part beyond the bracket has secured to it a large gear 18 engaged by a small gear 19 mounted on the end bracket, the shaft of said small 60 gear being provided with a sprocket wheel 20 carrying a chain 21 hanging therefrom. By the operation of said chain the door may be raised or lowered.

The lower door section 5^a is shown as provided near the chain with a handle 22 so that the door can be conveniently initially flexed at its hinges as shown in Fig. 3 to permit effective action of the draft of the cords to raise the door. This same handle can be 70 used for shoving the door sections into vertical coincidence for closing the door. In cross section the door members are elongated rectangles hence when the door is flexed at the hinge 6 as shown in Fig. 4 the upper 75 section is slightly raised because the sum of the diagonals of the two rectangles is greater than the sum of a pair of the sides, and conversely when the door is moved to completely closed position the upper door section 80 falls the lower edge of the lower section then resting squarely upon or very close to the floor. The upper door section in these movements moves in the direction of its plane.

The lower door section at its lower corners 85 is provided with rollers 23 journaled thereto as shown to travel on the faces of the usual tracks 24 for such doors. These rollers can be so located that when the door is flexed as shown in Fig. 4 the weight of the door is 90 supported by them. Bolts at 25 are provided for latching the lower door section and therefore the upper door section in fully closed position.

The forms of the parts can be changed 95 without departing from the gist of the invention as claimed.

What we claim is:

1. A door for a building including upper and lower sections hinged together, and stationary pins on the building and slotted pivoting members on the upper portions of the upper section slidingly engaging said pins, said connection permitting swinging move-

ment of said upper section as well as plane-
wise movement thereof in all positions there-
of.

2. A door for a building including upper
and lower door sections hinged together,
sliding pivoting members for the upper por-
tion of the upper door section and stationary

means on the building engaged by said piv-
oting members permitting planewise move-
ment of said upper section in all positions 10
thereof.

ALBERT RUSH.
RALPH H. GREEGOR.
